VICTOR J. REED, OF ROCKFORD, ILLINOIS, ASSIGNOR TO C. MATTISON MACHINE WORKS,
OF BELOIT, WISCONSIN, A CORPORATION OF WISCONSIN.

PORTABLE RUBBING-MACHINE.

1,122,640.

Specification of Letters Patent. Patented Dec. 29, 1914.

Original application filed August 9, 1913, Serial No. 783,656. Divided and this application filed November 6, 1913. Serial No. 799,600.

To all whom it may concern:

Be it known that I, VICTOR J. REED, a citizen of the United States, residing at Rockford, in the county of Winnebago and State 5 of Illinois, have invented a new and useful Portable Rubbing-Machine, of which the following is a specification, reference being had to the accompanying drawings and to the letters and figures of reference marked 10 thereon.

This invention relates to rubbing machines that are adapted for hand control and for various rubbing operations, such as sandpapering or polishing surfaces of furniture or other articles, the invention having 15 reference more particularly to a rubbing plate or block for holding sandpaper, rubbing felt or similar devices as shown in my Patent No. 1,099,617, issued June 9, 1914, of 20 which this application is a division.

An object of the invention is to provide improvements in portable rubbing machines, particularly with reference to means for expeditiously connecting a rubbing medium to 25 the machine, another object of the invention being to provide an improved rubbing plate which may be connected to the machine or may be adapted to be used separately by hand, and which shall be so constructed as 30 to enable the operator to quickly replace worn out abrading or rubbing devices, or to change such devices so as to adapt the implement for different classes of work.

With the above mentioned and other objects in view, the invention consists in interchangeable rubbing plates of novel construction provided with novel means for detachably securing rubbing sheets thereto and provided also with novel means for securing the 40 plates to rubbing heads, and the invention consists further in the novel parts and combinations and arrangements of parts as hereinafter particularly described and claimed.

Referring to the drawings, Figure 1 is an 45 end elevation of a rubbing machine to which the invention is applied; Fig. 2, a horizontal section approximately on the line A A in Fig. 1 (or more nearly on the line A' A' in Fig. 6.); Fig. 3, a fragmentary section 50 showing details of the improved rubbing plate; Fig. 4, a perspective view of one of the reciprocating heads of the machine inverted to which the rubbing plate is advantageously connected; Fig. 5, a perspective

view of one of the interchangeable rubbing 55 plates; Fig. 6, a longitudinal central sectional view of the rubbing machine, and Fig. 7 is a transverse section approximately on the line B B in Fig. 6.

Similar reference characters in the different figures of the drawings indicate corresponding elements or features of construction herein referred to and described in detail.

The rubbing machine with which the improved rubbing plate preferably is used may be variously constructed and operated, a simple form of construction comprising a suitable hollow frame 1 adapted to constitute an inclosing housing, the upper middle portion of which is raised and forms a hollow longitudinal rib serving as a journal box in which is a transverse opening 2, the top of the frame having a handle 3 thereon for manually controlling the machine. A 65 main shaft 4 is rotatably mounted in the hollow top portion of the frame and extends beyond the frame so that suitable driving means may be connected thereto, such as a flexible shaft or other means. A 70 bevel gear wheel 5 is secured to the shaft in the opening 2 for transmitting the motion imparted to the shaft. The under side of the top proper of the frame is designed so as to constitute a foundation 6 which is 75 provided with a downward extending stub shaft 7 on which a bevel gear wheel 8 is rotatably mounted and in mesh with the wheel or pinion 5, the wheel 8 being provided with a crank pin 9 for converting rotary 80 motion into reciprocating motion for operating the reciprocating heads. The under side of the top proper of the frame is provided also with a foundation plate 10 having a stub shaft 11 thereon that extends 85 downward, and an oscillatory lever 12 is rotatably mounted between its ends on the stub shaft, one end portion of the lever being provided with a wrist pin 13 to which a pitman 14 is connected, the pitman being 90 connected also to the crank pin 9 for actuating the lever, the latter having also a wrist pin 15 connected thereto in proximity to the wrist pin 13, and the opposite end portion of the lever 12 is provided with a 95 wrist pin 16. The lower side portions of the frame 1 are adapted to guide reciprocating heads and preferably are provided with sep-

100
105

arated guide bars 17 and 18 suitably secured thereto and behind which bearing strips 19 and 20 are arranged and suitably secured.

Two reciprocating heads 21 and 22 are comprised in the machine and are substantially alike but arranged in reverse order, end to end, and their edge portions in sliding arrangement with the guide bars and the wearing strips above described. The heads are provided respectively with arms 23 and 24 assisting to support two wrist pins 25 and 26 that are connected to the heads respectively and to the arms thereon. A pitman 27 is connected to the wrist pins 15 and 25 for moving and controlling the head 21, a pitman 28 being connected with the wrist pins 16 and 26 for operating and controlling the head 22.

The under side of the reciprocating head 21 is provided with transverse tapering jaw bars 29 and 30, the companion head being provided with similar bars 29' and 30', the outer sides 31 and 32 of the bars being cut under or inclined and also extend obliquely to the ends of the head so as to form wedges, and the bars 29 and 29' are provided respectively with guideways 33 and 33' that are adjacent to the under side of the heads.

The reciprocating heads are provided respectively with pivots 34 and 34' to which suitable levers 35 and 35' are connected, the levers being provided respectively with pivots 36 and 36' to which locking bars 37 and 37' are connected respectively, the locking bars extending slidingly into, and are movable through, the guideways 33 and 33' respectively for locking the rubbing plates to the reciprocating heads. The levers 35 and 35' may be variously latched and preferably are composed of spring-steel and have each a lip 38 formed thereon adapted to engage ratchet teeth 39 suitably arranged on the under side of the head.

The improved rubbing plates are substantially alike and are therefore interchangeable, and when adapted to be used in connection with the above described reciprocating heads, two rubbing plates, as 40 and 40', are provided to correspond with the number of heads comprised in the machine. The upper side of the rubbing plate 40 is provided with two tapering jaw bars 41 and 42, the plate 40', having similar bars 41' and 42' thereon, the inner sides 43 and 44 of the bars respectively being cut under or inclined and adapted to slidingly engage the outer sides of the two bars that are on each one of the reciprocating heads, so as to form a dovetail and wedging connection and draw the bars of the plate snugly to the heads. The opposite ends of each plate have bevel faces 45 and 46 respectively on the upper portions thereof against which to secure a sheet of sand paper or other rubbing medium. Each jaw bar 41 and 41' has a recess 47 therein

to receive either locking bar 37 or 37' which securely locks the plate to the head. The jaw bars that are on the rubbing plates have guideways 48 and 49 therein between their ends and adjacent to the upper side or top 70 of the rubbing plate, one jaw bar having also two guideways 50 and 50' in proximity to the two end portions thereof respectively, the companion jaw bar having similar guideways 51 and 51' therein. Each rubbing plate is provided with two pivots 52 and 53 to which two clamping levers 54 and 55 are respectively connected, the levers extending transversely to the rubbing plate and are provided with pivots 56 and 57 to 75 which operating bars 58 and 59 are connected respectively and arranged so as to extend through the guideways 48 and 49 and also over the bevel faces 45 and 46 respectively. Two clamp bars 60 and 61 are secured to the outer ends of the operating bars respectively and so as to extend opposite to and parallel with the opposite ends respectively of the rubbing plate, the inner edges of the bars 80 preferably having inclined faces 62 and 63 85 respectively that correspond approximately to the bevel faces 45 and 46, so that when the clamp bars are drawn forcibly against the bevel edges, the inclined faces are forced slightly up the bevel faces so as to tightly 90 draw sheets of sandpaper or other material on the working face of the rubbing plate. The clamp bar 60 preferably is provided with two guide bars 64 and 65 that are slidingly guided in the guideways 50' and 50 95 respectively, the clamp bar 61 being provided with similar guide bars 64' and 65' that are slidingly guided in the guideways 51 and 51' respectively. A pair of suitable rubbing sheets 66 and 66', such as sandpaper, felt or other material, are secured to the respective plates by means of the clamp bars thereon, as shown more fully in Fig. 6. The clamp levers 54 and 55 may be variously 100 latched to the rubbing plate and may suitably be composed of spring-steel and have lips 67 and 68 formed thereon respectively and adapted to engage ratchet teeth 69 and 70 respectively formed on the upper side of 105 the rubbing plate.

In practical use, a suitable covering is placed on the under side of each rubbing plate, one end of the sheet being drawn up over the bevel face of one end of the plate and secured thereto by the adjacent clamp 110 bar, after which the opposite end of the sheet is turned up over the bevel face of the opposite end of the plate and independently secured thereto by means of the adjacent 115 clamp bar, the clamp bar tending to draw or stretch the sheet tightly on the rubbing plate. The rubbing plate may be handled by hand or it may be connected to either one of the reciprocating heads as above explained. The result of the operation of the 120 125 130 135

gearing of the machine obviously will be fully understood from the description of the construction and function of the different elements thereof, without further explanation in detail.

Having thus described the invention, what is claimed as new is—

1. A rubbing device including a plate having two end portions that are beveled on their upper or back sides, and two clamp bars movably arranged independently opposite to the beveled end portions respectively to coöperate therewith and independently guided by the plate.

15 2. A rubbing device including a plate having a bevel face on the normal back or upper portion of one end thereof, and a clamp bar movably arranged adjacent to and opposite the bevel face to coöperate therewith and having an operating bar that is slidingly guided by the plate.

25 3. A rubbing device including a plate having a bevel face on the normal back or upper portion of one end thereof, a clamp bar movably arranged opposite the bevel face to coöperate slidingly therewith and having an operating bar and also two guide bars that are movably guided by the plate.

30 4. A rubbing plate having a bar on its normal back or upper side adjacent to one end thereof, the bar having a plurality of separate guideways therein, and a clamp bar movably arranged adjacent to the end of the plate to coöperate therewith and having an operating bar and also guide bars that are movably guided in the guideways respectively.

35 5. A rubbing device including a stationary plate having a guideway on its normal back or upper side adjacent to one end thereof, and a clamp bar movably arranged adjacent to the end of the plate to coöperate therewith and having an inclined under face that is oblique to the front face of the plate and opposed to the normal upper side of the end, the bar having an operating bar that is slidingly guided in the guideway.

40 6. A rubbing device including a plate having two end portions that are beveled on their normal back or upper sides, two clamp bars movably arranged opposite to the beveled end portions respectively and provided with operating bars and also guide bars respectively that are guided on the upper sides of the plate, and independent means for independently operating the operating bars respectively.

45 7. A rubbing machine including a reciprocating head, a rubbing plate detachably secured to the head and having two end portions that are beveled on their normal back

or upper sides, two clamp bars movably arranged opposite to the beveled end portions respectively and provided with operating bars and also guide bars respectively that are slidingly guided by the plate, and two hand levers pivotally connected to the plate and also to the respective clamp bars.

50 8. In a rubbing machine, a plate having two opposite beveled ends, and two clamp bars arranged opposite said ends respectively and having each a guide bar that is movably guided by said plate to slide upon said beveled ends, in combination with means for operating said bars and securing them independently on said beveled ends.

55 9. In a rubbing machine, a plate having stationary guideways on the back or normal upper side of two opposite end portions thereof, two clamp bars movably arranged adjacent to the opposite ends respectively of the plate to coöperate therewith and having guide bars slidingly guided in the respective guideways, and independent means co-operating with the plate for independently moving the clamp bars and holding them to the adjacent ends of the plate.

60 10. In a rubbing machine, the combination of a head provided with two jaw bars and a locking bar and also a lever connected to the locking bar, and a rubbing plate provided with two jaw bars wedgingly engaging the jaw bars of the head, the plate having a recess to receive the locking bar and provided with two independently movable clamp bars on opposite ends thereof, each clamp bar being provided with an operating lever coöoperating with the plate to draw the clamp bar to the adjacent end of the plate.

65 100 11. A rubbing device comprising a plate having two bevel faces on the upper side of two opposite ends thereof respectively and also guideways on the upper side adjacent to said faces, two clamp bars movably arranged adjacent to said ends respectively and having inclined under faces opposite to said bevel faces respectively, the two clamp bars being provided respectively with two operating bars that are slidingly guided in two of said guideways respectively, said clamp bars having also guide bars that are slidingly guided in others of said guideways, and two operating levers pivoted to said plate and also pivoted to the two operating bars respectively.

70 105 In testimony whereof, I affix my signature in presence of two witnesses.
